PRESS CONTROL

Leslie S. Hubbert, Mount Gilead, Ohio, assignor
to The Hydraulic Development Corporation,
Inc., Wilmington, Del., a corporation of Delaware

Application November 5, 1943, Serial No. 509,041

3 Claims.

(Cl. 60—52)

1

This invention relates generally to hydraulic presses and has for its primary object the provision of a manual and automatic control linkage whereby it is possible accurately to control the rate of travel and position of the press platen during its reciprocation to and from the work.

In many classes of work, such as bending and straightening and some forging operations, it is desirable that the press platen be under the control of the operator at all times both as to position and rate of travel. Particularly in the straightening of shafts and similar objects precise positioning of the press platen relative to the work is essential. In an operation of this type, it is also desirable that the operator be able to retract the platen from the work a short distance in order to gage the work piece or insert a new one as the case may be.

By means of the control system of this invention, it is possible to accomplish these results readily.

The foregoing will be more apparent upon reference to the following detailed description taken in connection with the attached drawings. In the drawings:

Figure 1 is a rather diagrammatic view of a hydraulic press having a control system embodying this invention.

Figure 2 is a view of one form of hydraulic system adapted to be controlled by this control system.

Figure 3 is a wiring diagram of the electrical system associated with this control.

Referring to the drawings more in detail, and in particular to Figure 1, the hydraulic press shown therein comprises a frame member generally indicated at 10 having bed portion at 11 and carrying a press cylinder at 12.

Reciprocably mounted within the cylinder 12 is a press ram or platen 13 adapted to move into and out of engagement with the work as determined by the operator.

Mounted within the press frame 10 are hydraulic pumps 14 and 15, the former being a variable delivery pump and the latter being a constant delivery pump. These pumps are connected through a suitable network of conduits with the conduits 16 and 17, which last mentioned conduits serve to conduct fluid to the interior of the cylinder 12 and whereby to reciprocate the ram 13.

Referring now to Figure 2, the aforementioned hydraulic system is more completely illustrated. In this view the pump 14 is connected on one side by the conduit 18 to the conduit 16, and on

the other side by the conduit 19 to the conduit 17. The pump 15 is adapted to draw fluid from the tank 20 through the conduit 21 and to expel it, at increased pressure, into the conduit 22 which joins through the check valve 23 with the conduit 16, and through the check valve 24 with the conduit 17. The conduit 22 further comprises a relief valve 25 which is adapted, upon the accomplishment of a predetermined pressure within the conduit 22, to establish a fluid connection from the conduit 22 through the conduit 26 back to the tank 20. Valve 25 is preferably a low pressure relief valve and serves to discharge the excess discharge of the pump 15 when it is not desired to utilize the full flow from the pump 15 in the operation of the press.

The conduit 16 includes, between the cylinder 12 and the junction of conduits 16 and 18, a valve 27. This valve, which is an unloading or pilot operated relief valve, is for the purpose of discharging the fluid above the ram 13 to the tank during the retraction stroke. This is necessary because the amount of fluid discharged from above the ram during the retraction stroke is in excess of the amount introduced into the cavity beneath the ram during the retraction stroke. The valve 27 connects through the conduit 28 and the low pressure relief valve 29 with the tank 20. A pilot line 30, the function of which is to operate the valve 27, is connected to the conduit 17 at one end and into the pilot cylinder of the valve 27 at its opposite end.

The low pressure relief valve 29 in the conduit 28 is for the purpose of maintaining sufficient pressure within the conduit 28 to maintain the hydraulic system completely filled at all times.

Referring again to Figure 1, more particular reference will be made to the previously mentioned control system.

This system comprises a screw 31 which threads through an arm 32 carried by the ram 13. The screw 31 is journaled in the press frame 10 as at 33 and passes through the gear box 34 of the motor 35 within which it is suitably splined or slidably keyed to the low speed output gear of the gear box. The lower end of the screw 31 is splined as at 36 and carries a similarly splined bevel gear 37. The screw 31 also has pinned thereto a pair of collars 38 which are adapted, as indicated in Figure 1, to engage the end of a bell crank lever 39 by means of which the valve delivery pump 14 is shifted. The lever 39 is pivoted at 40 on the press frame or any other similarly stationary member.

The gear 31 is in mesh with the bevel gear 41,

which latter gear is pinned to the shaft 42. The shaft 42 extends leftwardly from the gear 41 towards the front of the press and has pinned or otherwise suitably affixed to its left end the clutch member 43.

In engagement with the clutch member 43 is a mating clutch member 44 splined or keyed in any other suitably slidable manner to the right hand end of a shaft 45. The shaft 45 extends leftwardly through the wall of the bed portion 11 of the frame 10 and has affixed to the end thereof and outside of the press bed the hand wheel 46. A pinned collar or other suitable means such as indicated at 47 retains the shaft 45 in its proper position in the press bed.

The previously mentioned clutch members 43 and 44 comprise a magnetically operated clutch, actuation of which is effected through the lever 48, the solenoid 49 and the spring 50. The lever 48 is pivoted at 51 and is adapted, when the solenoid 49 is energized to rotate clockwise thereupon and bring the clutch members 44 and 43 into driving engagement. Upon deenergization of the solenoid 49 the spring 50 is effective to rotate the lever 48 counter-clockwise about the pivot 51 and thereby to move the clutch member 44 away from the clutch member 43 thus destroying the driving connection therebetween.

The motor 35 is adapted to drive the screw 31 through the gear box whereby to cause reciprocation of the press platen in a manner herein-after described.

Referring now to Figure 3, there is illustrated the electric circuit employed to energize the motor 35 and the clutch solenoid 49. The circuit shown in Figure 3 comprises the electric mains 52 and 53 connected between which are the branches including the push buttons, contactors, solenoids and motor which comprise the electric circuit.

The first branch line contains a push button 54 and a contactor solenoid A. A second line includes clutch solenoid 49 and the normally closed contactor blades A1 and B1. The third branch line includes a motor 35 and a pair of normally open contactor blades A2. In parallel with A2 and also connected to the motor is a branch containing the normally open contactor blades B2. A last branch line includes the contactor solenoid B and the push button 55.

The motor 35 is of the well known electrically reversible type and is adapted, when energized by the means of the mains 52 and 53 through the blades A2 to rotate in one direction, and when energized through the blades B2 to rotate in the opposite direction.

Operation

Assuming that the press ram is in the position shown in Figure 1, and that a work piece, as indicated by the dot-dash lines, is resting on the press bed, a work stroke will be instituted by the operator by pressing the push button 54. Closing of the push button 54 will energize the contactor solenoid A. Energization of the contactor solenoid A causes the normally closed blades A1 to open and the normally open blades A2 to close. The opening of the blades A1 de-energizes the previously energized clutch solenoid 49 and the closing of the blades A2 energizes the motor 35 to rotate in one direction.

The deenergization of the clutch solenoid 49 permits the spring 50 to open the clutch thereby disconnecting the driving connection between the hand wheel 46 and the screw 31. The rota-

tion of the motor 35 is effective to rotate the screw 31 through the gear box 34. Rotation of the screw 31 causes it to thread upwardly through the arm 32 and, by means of the collars 38 causes the bell crank 39 to shift the pump 14.

The shifting of the pump 14 causes fluid to be delivered into the conduit 18 and thence through the conduit 16 into the chamber within the cylinder 12 and above the press ram 13. Fluid is also withdrawn from beneath the ram 13 through the conduit 17 and conduit 19. The press ram 13 moves downwardly due to this fluid transfer and carries with it the arm 32. Downward movement of the arm 32 tends to move the screw 31 downwardly to offset the previously mentioned upward movement of the screw 31 relatively to the arm 32. It will be apparent that the rate of movement downwardly of the press ram 13 and attached arm 32 will be equal to the rate at which the screw 31 threads upward through the arm 32. For this reason, the pitch of the screw 31 and the rate at which it is driven are dependent upon the rate at which the pumps 14 and 15 can supply fluid to cylinder 12. The maximum rate at which the screw 31 threads upwardly through the arm 32 must be equal to the maximum rate at which the ram 13 descends due to the aforementioned transfer of fluid to and from the cylinder 12 by the pumps 14 and 15.

The button 54 is held closed by the operator until the ram 13 approaches the work at which time the button 54 is permitted to open and the press ram halts. During this portion of the forward stroke, which is conducted at relatively high speed, the action of the hydraulic circuit illustrated in Figure 2 is as follows:

The pump 14 is shifted, by means of the bell crank 39, to deliver fluid into the conduit 18 and thence, by means of the conduit 16, into the chamber above the press ram 13. The pump 14 also draws fluid through the conduit 19 and 17 from beneath the press ram 13. The weight of the ram 13 and the associated parts is sufficient to cause the moving parts of the press to descend as rapidly as fluid is withdrawn from the cylinder 12 through the conduits 17 and 19. During this part of the forward stroke, the pump 15 delivers fluid through the check valve 23 into the conduit 16 and thereby makes up the difference between the amount of fluid withdrawn from beneath the ram by the pump 14 and the amount of fluid required to fill the cavity above the ram 13.

Also, withdrawal of fluid from the cylinder 12 through the conduit 17 will cause the pressure therein to be reduced to such as value that the valve 27, piloted by this pressure, will close. The closing of the valve 27 seals off the fluid connection between the conduits 16 and 28 and thereby directs the discharge of pumps 14 and 15 directly into the cylinder 12 above the ram.

As previously mentioned, when the press ram approaches the work the push button 54 is permitted to open thereby deenergizing the contactor solenoid A and opening the contactor blades A2 to stop the motor 35. Deenergization of the contactor solenoid A also permits the blades A1 to close thereby energizing the clutch solenoid 49. The operator may now control the movement of the press ram 13 by rotation of the hand wheel 46 as follows:

Rotation of the hand wheel 46 is communicated, by means of the shaft 45, the now engaged clutch members 44 and 43 and the shaft 42 into

the bevel gear 41. Rotation of the bevel gear 41 causes rotation of the mating bevel gear 31 which, through its splined connection therewith, rotates the screw 31. In the manner described above, in connection with automatic rotation of the screw, manual rotation of the screw 31 will cause a corresponding reciprocation of the ram 13. The ram 13 is thereby reciprocated by a manipulation of the hand wheel 46 to occupy any position desired by the operator.

For example, in the straightening of a shaft, it might be desired to move the platen 13 into engagement with the work, to further force the platen under pressure into the work, and then to retract the platen slightly away from the work in order to gage or otherwise measure the effect produced. Having caused the platen to approach the work under high speed, this is readily accomplished by means of the manual control at 46.

Retraction of the ram from the work to the position indicated in Figure 1, or any intermediate position, may be accomplished at relatively high speed by the closing of the push button 55. The closing of the push button 55 energizes the contactor solenoid B and thereby causes the normally open blades B2 to close and the normally closed blades B1 to open. The opening of the blades B1 deenergizes the clutch solenoid 49 and permits the spring 50 to open the clutch as previously described. The closing of the blades B2 energizes the motor 35 to rotate in a direction opposite to that caused by the closing of the blades A2. The rotation of the motor 35 drives the screw 31 in a direction to thread downwardly through the arm 32. Movement of the screw 31 downwardly through the arm 32 causes the collars 38 to move the bell crank 39 to shift the pump 14 on stroke. The pump 14 now draws fluid in through conduit 18 and discharges fluid through conduit 19. The fluid discharge into the conduit 19 is conducted by means of the conduit 17 into cylinder 12 and beneath the press ram 13.

The passage of fluid through the conduits 19 and 17 into the cylinder 12 causes an increase in pressure in the conduit 17 which is communicated through the pilot line 30 to the pilot cylinder of the unloading valve 27. The valve 27 is thus caused to establish a fluid connection between the conduits 16 and 28, and the fluid expelled from above the press ram 13, in excess of the amount required to fill the cavity beneath the press ram 13, is passed through the conduit 28 and the low pressure relief valve 29 to the tank 20. During this retraction stroke the pump 14 is either discharging through the relief valve 25 to the tank or through the check valve 23, valve 27, conduit 28 and relief valve 29 to the tank.

It will be apparent that the retraction area of the press ram 13 is of sufficient size that the full delivery of the pump 14 is sufficient to cause upward movement of the press ram to be equal to the maximum rate of downward movement of the screw 31 as the screw threads downwardly through the arm 32.

It will be noted that the clutch solenoid 49 is adapted to be continuously energized so long as the contactor blades A1 and B1 are closed. The energization of either of the contactor solenoids A or B is effective to render inoperative the hand wheel 46. This is a safety feature insuring that there is never a driving connection between the screw 31 and the hand wheel 46 when the motor 35 is energized to drive the screw 31 at high speed. It is possible to move the screw 31 by

means of the hand wheel 46 when and only when, the motor 35 is deenergized.

It will be obvious that, due to the nature of the pump 14, the effect of the screw 31 is to give a micrometer adjustment of the platen position. That is, the rate of reciprocation of the platen is dependent upon the amount by which the pump 14 is shifted on to stroke, and that the amount that the pump 14 is shifted is in turn dependent upon the speed of rotation of a screw 31.

It is further apparent that the flow regulating means need not necessarily consist of a variable delivery pump but could as well consist of a four way valve connected with the screw 31 either directly or through linkage similar to the lever 39.

It will be understood that I do not desire my invention to be limited to the particular structure shown in the drawings but desire to comprehend such modifications as may come within the spirit of the invention and the scope of the appended claims.

Having thus fully described my invention, what I claim as new and desire to secure by Letters Patent is:

1. In a hydraulic press, a press platen, fluid motor means for reciprocating said platen, a source of pressure fluid, means forming a hydraulic circuit connecting said source with said motor and including control means for varying the rate of fluid flow, a rod threadedly engaging said platen for movement therewith and including means operatively connected with said control means, a reversible electric motor slidably keyed to one end of said rod selectively operable for rotating the said rod in either direction, manual means slidably keyed to the opposite end of said rod extending to the operator's position and operable to rotate said rod in either direction, normally open switch means selectively operable to energize said motor to operate in either direction, electrically actuated clutch means between said rod and said manual means operable when energized to disengage said manual means from said rod, and contactor means connected to be energized by said switch means and having contactor blades in circuit with said motor and said clutch means for positively deenergizing said clutch means simultaneously with the energization of said motor.

2. In a hydraulic press, a platen, a fluid motor for reciprocating said platen, a variable delivery pump connected to supply said motor, flow control means operable to control the rate and direction of the fluid supply from said pump to said motor, a threaded rod threadedly engaging said platen in a direction substantially parallel to the path thereof, an electric motor slidably keyed to the upper end of said rod for selectively rotating the same in either direction, manual means slidably keyed to the lower end of said rod and extending to the front of the press to the operator's position for manual actuation of said rod in either direction, means on said rod between the ends thereof for engagement with said flow control member whereby movement of said rod in the axial direction is operable to adjust the rate of flow from said source, normally open switch means adapted for selectively energizing said motor to run in opposite directions, normally open clutch means between said manual means and said rod, and a solenoid adapted, when energized, to move the clutch to closed position, said solenoid being connected to be energized when said motor is de-energized and to be

de-energized when said motor is energized whereby said manual means is always disconnected when said motor is operating.

3. In a hydraulic press, a press frame, a plunger reciprocably mounted in said frame, a reversible variable delivery pump for supplying fluid to said plunger control means movable to vary the rate and direction of delivery of said source for controlling the movement of said plunger, an arm carried by said plunger including a threaded bore, a threaded rod slidably mounted in said frame and engaging said bore, linkage interconnecting said rod and said control means for moving the latter in unison with the former, a reversible electric motor mounted 15 in said frame adjacent the upper end of said rod,

slidable key means interconnecting said motor and said rod, a bevel gear slidably keyed to the lower end of said rod, a second bevel gear in mesh with said first mentioned gear, a shaft extending from said second gear through said press frame to the operator's position, manual means for turning said shaft, clutch means for connecting the manual means to the shaft and normally urged to disengaged position and having electrical means adapted when energized to move the clutch to engaged position, and circuit means interconnecting said electrical means with said motor and so arranged that when either is energized the other is de-energized.

LESLIE S. HUBBERT.
